(57) **CLAIM**

The ornamental design for a drum cartridge, as shown and described.

DESCRIPTION

FIG. 1 is a front, right side, top perspective view of a drum cartridge showing our new design;

FIG. 2 is a rear, left side, top perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of the portion within the broken-line box 9 shown in FIG. 3 thereof;

FIG. 10 is an enlarged view of the portion within the broken-line box 10 shown in FIG. 3 thereof;

FIG. 11 is an enlarged view of the portion within the broken-line box 11 shown in FIG. 4 thereof;

FIG. 12 is an enlarged view of the portion within the broken-line box 12 shown in FIG. 4 thereof;

FIG. 13 is an enlarged left side view thereof;

FIG. 14 is an enlarged right side view thereof;

FIG. 15 is an enlarged view of the portion within the broken-line box 15 shown in FIG. 7 thereof;

FIG. 16 is an enlarged view of the portion within the broken-line box 16 shown in FIG. 7 thereof;

FIG. 17 is an enlarged view of the portion within the broken-line box 17 shown in FIG. 8 thereof;

FIG. 18 is an enlarged view of the portion within the broken-line box 18 shown in FIG. 8 thereof;

FIG. 19 is an enlarged view of the portion within the broken-line box 19 shown in FIG. 1 thereof;

FIG. 20 is an enlarged view of the portion within the broken-line box 20 shown in FIG. 1 thereof;

FIG. 21 is an enlarged view of the portion within the broken-line box 21 shown in FIG. 2 thereof; and,

FIG. 22 is an enlarged view of the portion within the broken-line box 22 shown in FIG. 2 thereof.

The dot-dash broken-line boxes make reference to portions shown in enlargement views and form no part of the claimed design.
